UNITED STATES PATENT OFFICE.

HERMAN WESTLING, OF MARSHALLTOWN, IOWA.

APPAREL-FASTENER.

SPECIFICATION forming part of Letters Patent No. 782,090, dated February 7, 1905.

Application filed February 16, 1904. Serial No. 193,797.

To all whom it may concern:

Be it known that I, HERMAN WESTLING, a citizen of the United States, residing at Marshalltown, in the county of Marshall and State 5 of Iowa, have invented certain new and useful Improvements in Apparel-Fasteners, of which the following is a specification.

The objects of my invention are to provide a fastening device especially adapted for use 10 in connection with apparel-leggings and so arranged that the wearer may by simply pulling upon a cord bring the overlapping sides of the legging together, and when together the legging will be firmly held by metal pins on one 15 member entering metal eyelets on the other member, so that the strain upon the legging will be thrown entirely upon the metal parts instead of the cord, and, further, to provide a fastener of this kind in which the cord is protected from wear.

My invention consists in certain details in the construction, arrangement, and combination of the various parts of the device whereby the objects contemplated are attained, as here- 25 inafter more fully set forth, pointed out in my claims, and illustrated in the accompanying drawings, in which--

Figure 1 shows a perspective view of a legging with my improved fastening device applied thereto, the legging being partly open; and Fig. 2 shows a transverse sectional view of the overlapping sides of the legging through one of the fastening devices.

Referring to the accompanying drawings, I 35 have used the reference-numeral 10 to indicate the body portion of the legging, which may be made of woven fabric or any suitable material and which is of the class of leggings having overlapping end portions at one side of the 40 legging. At the bottom of the legging is a strap 11, having a buckle 12 to provide for holding the legging down. Attached to the inner face of the inner one of the overlapping ends is a metal strip 13, extended longitudinally of the legging and protected by the fabric strip 14, secured to the inner face of the legging. I have provided a number of pins 15, each having an eye through its outer end and a shank 16 of smaller diameter near its inner 45 end, which shank is passed through the metal 50

strip 13. A head 17 is formed on the inner end of the pin and secures the pin firmly to the said strip 13. These pins are placed at regular intervals throughout the length of the legging. The outer one of the edges of the legging is provided with a series of metal eyelets 18, large enough to admit the outer ends of the pins 15 and spaced on the legging as required to receive the projecting ends of the pins when the outer edge is placed in position overlapping the inner edge. I have also provided a flexible cover 19 to overlap the outer edge of the legging and to conceal and protect the fastening devices. This cover 19 is provided near the center of the legging with two small 65 eyelets 20 near each other and also with two small eyelets 21 near each other near the top of the legging.

The numeral 22 indicates a cord having a knot 23 at one end. This cord is passed first 70 through the eye in the end of the lower pin 15, then outwardly through the lower eyelet 18, then inwardly near the second eyelet 18, then through the second pin, and then outwardly through the second eyelet, and so on 75 until the cord is passed through the eyelets 20, which eyelets are located between two of the pins 15. Then the cord is again passed through the next eyelet 18, above the eyelets 20, and so on until the top portion of the legging 80 is reached. Then the cord is passed through the eyelets 21 near the top of the legging, and the upper end of the cord extends through the upper eyelet 18. The lower end of the flap 19 is held in position by a strap 19^a, of 85 the ordinary kind.

In practical use and assuming that my improved fastener is applied to a legging as shown and described the operator first separates the edges of the legging, as shown at 90 the top of Fig. 1, whereupon the operator may pass his foot through the legging. Then by pulling at the upper end of the cord draw the lower eyelet 18 along the doubled cord passed through it until said eyelet passes over 95 the projecting end of the lower pin. Each eyelet 18 will in turn be drawn into position with its mating pin passed through it, and the cords will firmly hold the eyelets over the pins. Furthermore, the flap 19 will be firmly held 100

against the ends of the pins 15, thus protecting the cord from wear and concealing the entire cord and fastening devices, except between the pairs of eyelets 20 and 21. The cord may be 5 knotted at the top, thus preventing it from being pulled downwardly and releasing the fastening device. In this way the wear upon the fastening devices will be thrown upon the metal pins and eyelets, and therefore the cord 10 will be protected and will last a comparatively long time. By thus concealing and protecting the cord and fastening devices there will be no projecting parts to engage and wear out an overcoat or outer garment of the wearer 15 15 which might be rubbed by the legging, and there are no projecting parts on the leggings to be caught in underbrush through which the wearer may be passing.

Having thus described my invention, what 20 I claim, and desire to secure by Letters Patent of the United States therefor, is—

1. The combination with an article of wearing-apparel having inner and outer overlying portions, of a number of pins passed through 25 one of said overlying portions each pin formed with an eye, eyelets in the other overlying

portion of the article designed to receive said pins, a flap overlapping said eyelets and formed with eyelets, and a cord passed through the eyes of the pins, between the overlying portion having a flap and the flap, said cord also passed through the eyelets in said flap. 30

2. An apparel-legging having inner and outer overlying portions at one side, a metal strip on the inner surface of the inner overlying portion, a protecting-strip covering the inner face of the metal strip, a number of metal pins riveted to the metal strip and projected through the inner overlying portion, the outer ends of the pins each formed with 40 an eye, eyelets in the outer overlying portion, a flap secured to the outer surface of the outer overlying portion having a number of pairs of eyelets therein and a cord passed through the eye of each pin, between the outer 45 overlying portion and the flap, and through the pairs of eyelets in the flap.

HERMAN WESTLING.
